CLAIM

The ornamental design for a furniture leg protector, as shown and described.

DESCRIPTION

FIG. 1 is a front and top perspective view of a first embodiment of a furniture leg protector, showing my new design;

FIG. 2 is a rear and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front and top perspective view of a second embodiment of the furniture leg protector, showing my new design;

FIG. 10 is a rear and bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a front and top perspective view of a third embodiment of the furniture leg protector, showing my new design;

FIG. 18 is a rear and bottom perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof; and,

FIG. 24 is a bottom view thereof.

The broken lines in the figures illustrate portions of the furniture leg protector that form no part of the claimed design.
